RECIPROCATING SUCTION PUMP

Benjamin Gambarini, Alameda, Calif.

Application February 19, 1935, Serial No. 7,182

1 Claim. (Cl. 103—76)

This invention relates to reciprocating suction pumps such as are used in wells. These pumps ordinarily employ plungers or pistons having cup leathers, which must be frequently pulled for replacement when worn, to prevent undue loss of the necessary suctional force.

The particular object of my invention is to construct a pump of the above general character in which the usual piston and rod are eliminated, 10 and the pipe column within the well casing serves as the piston.

The above and other objects are carried out by means of the structure shown in the accompanying drawing in which Figure 1 is a side 15 elevation foreshortened, of my improved pump structure;

Figure 2 is an enlarged sectional elevation of the same;

Figure 3 is a fragmentary section of the pump 20 column showing an auxiliary supporting or balancing spring arrangement.

Referring to the numerals of reference on the drawing, and particularly at present to Figures 1 and 2, 1 denotes the well casing, supported by and depending from a base 2. This casing 25 has a valve chamber 3 on its lower end, in which is mounted an upwardly opening gravity seated intake valve 4.

Freely slideable in the casing above the chamber 3 is the pump column, made of a number of connected lengths of pipe 5 as usual, the upper one projecting a short distance above the casing and base. An elbow 6 is fitted on the upper 35 end of the column, from which a discharge nipple 7 projects.

A compression spring 8 is disposed about the column between the elbow and the base 2, and is of sufficient strength to support the weight of the column.

Fitted in the lower end of the column is a 40 valve cage and seat 9, cooperating with an upwardly opening gravity seated valve 10, which closes the lower end of the column.

The elbow 6 at a point axially of the pump 45 column, is flexibly connected to the strap 11 of an eccentric 12. This eccentric is mounted on a shaft 13 journaled on a rigid framework 14 standing from the the base 2. The shaft is provided with a pulley 15 and a balancing flywheel 50 16, the pulley being belt-connected to a prime mover such as an electric motor 17 mounted on the base 2.

In operation it will be seen that as the motor 55 is driven the pump column will be reciprocated by reason of its connection with the eccentric.

As the column descends, any water trapped in the casing chamber 3 will force the valve 10 open and enter the pump column. As the column lifts, the valve 10 of course closes, while the valve 4 will open due to the suctional effect set 5 up with the upward movement of the pump column, and water will enter the chamber 3.

Repeated reciprocations of the pump column of course cause the water to accumulate and raise in the column, until it reaches and flows 10 from the discharge nipple at the top.

The speed at which the pump column is reciprocated depends upon the depth of the well and the internal diameter of the column and the volume of water which may be expected at the 15 discharge orifice of the pump is dependent on the length of stroke of the pump column.

The first two of these factors determine the weight of the body of water being lifted, and since there exists a critical speed, at which the 20 pump column and the body of water contained therein would be oscillating in synchronism, reciprocation of the column at a frequency in excess of this critical speed is required in order to effect removal of water from the well. 25

It has been found that, in a well having a depth of approximately 100 feet, a column of about 2 inches diameter reciprocated at a speed of about 300 to 350 cycles per minute will effect removal 30 of a satisfactory amount of water. With a stroke of sufficient magnitude, it appears that, within these speed limits, the water contained within the column is given a definite momentum upwardly which persists even during a portion of the downward or return stroke of the column. 35 There actually exists therefore an oscillatory phase difference between the column and the body of water and it is this difference which produces the flow of water at the discharge orifice. 40

In the event that the weight or length of the pump column is such that a single spring at the top is insufficient to properly support the depending weight, I may mount an additional 45 supporting spring 18, as shown in Figure 3, at any desired point in the length of the column.

In this arrangement, the top of the spring engages a cup 19 secured on the adjacent length of pipe 5A.

The lower ends of the spring rests on the lower 50 end of an enlarged coupling member 20 which connects adjacent section of the well casing 1A and forms a housing about the spring so that the latter may have unrestricted freedom of 55

action without rubbing against the wall of the casing.

Having described my invention, what I claim is:

- 5 In a well pump comprising a sectional tubular pump casing adapted to be placed in a well bore and terminating at its lower end below the level of the water in said well, an upwardly opening valve in, and closing the lower end of, said casing, a tubular pump column disposed within said pump casing, said pump column having an upwardly opening valve in the lower end thereof, and a discharge outlet at the upper end thereof, means for reciprocating said pump column with-
10
15 in said pump casing, and means for resiliently

supporting said column in said casing, said means comprising a coupling section secured to an end of one of said casing sections, a sleeve connected to said coupling section and to the adjacent end of another of said casing sections, a tubular member secured to said coupling section and disposed about said pump column, a cup-shaped member secured to said pump column in axially spaced relation to said tubular member, and a coil spring disposed between said coupling section and said pump column, said spring being positioned partly within said cup-shaped member and partly exterior of said tubular member. 5 10 15
